US0D1091919S

(12) **United States Design Patent** (10) **Patent No.:** **US D1,091,919 S**
(45) **Date of Patent:** **** Sep. 2, 2025**

(54) **LIGHT FIXTURE**

(71) Applicant: **Buster and Punch Limited**, Stamford
(GB)

(72) Inventors: **Iain Dulley**, Winchester (GB);
Massimo Minale, London (GB)

(73) Assignee: **Buster and Punch Limited**,
Peterborough (GB)

(**) Term: **15 Years**

(21) Appl. No.: **29/805,409**

(22) Filed: **Aug. 26, 2021**

Related U.S. Application Data

(62) Division of application No. 29/734,506, filed on May
13, 2020, now Pat. No. Des. 932,678, which is a

(57) **CLAIM**

The ornamental design for a light fixture, as shown and described.

DESCRIPTION

FIG. 1 is an isometric view of a light fixture showing a design according to the present disclosure.

FIG. 2 is a front view thereof, with the back view being identical.

FIG. 3 is a side view thereof, with the opposing side view being identical; and,

FIG. 4 is a bottom view thereof.

The top of the light fixture does not form part of the claimed design.

The broken lines in the drawings illustrate portions of the light fixture that form no part of the claimed design.

1 Claim, 4 Drawing Sheets

Related U.S. Application Data

division of application No. 29/617,213, filed on Sep. 12, 2017, now Pat. No. Des. 887,067.
